UNITED STATES PATENT OFFICE.

ALFRED PASQUEAU, OF LYONS, FRANCE.

CLOUGH-DAM OR SLUICE-WEIR.

SPECIFICATION forming part of Letters Patent No. 225,533, dated March 16, 1880.

Application filed January 19, 1880.

To all whom it may concern:

Be it known that I, ALFRED PASQUEAU, of the city of Lyons, in the Department of the Rhone, and Republic of France, have invented 5 a certain new and useful Improvement in Clough-Dams or Sluice-Weirs; and I do hereby declare that the following is a full, clear, and exact description of the invention, which will enable others skilled in the art to which it applies 10 pertains to make and use the same, reference being had to the accompanying drawings, which form a part of this specification, and in which—

Figure 1 is a sectional side elevation illustrating the application of my invention. Fig. 15 2 is a top or plan view of the sliding shutter-brace abutment, and Fig. 3 is a longitudinal vertical section of the same through line $x-x$ in Fig. 2.

Similar letters of reference indicate corresponding parts in all the figures.

My invention has relation to movable clough-dams or sluices used in rivers or channels for the purpose of causing overflow by damming 25 up the water, or for the purpose of increasing the depth of water in the river or channel at any given point or points.

As heretofore constructed this class of dams consists of a series of detached shutters placed 30 in a line with each other transversely across the channel or river, and hinged at their lower ends to sills or piers which are embedded into or built up from the channel or river-bed, and which are therefore liable to obstruct 35 navigation and impede the flow of the current when the dam is down.

My improvement consists in the construction and arrangement of a channeled abutment provided with a series of steps or shoulders forming inclined planes leading from one to the other, and which operates in combination with detachable shutters hinged by their middle to supports or braces, the lower free ends of which are adjustable in the channels 45 or grooves of the abutment, and impinge upon its steps or shoulders, substantially as herein-after more fully described.

In the annexed drawings, A, Fig. 1, represents the riverbed or bottom, and C C' the sectional dam or shutters, one of which is shown up and the other down. The number of these

shutters, which are all of equal width and height, will, of course, depend upon the width of the water-course which is to be dammed up. Each of the shutters C is hinged by its middle 55 to a brace, D D', and is provided with a supplemental support or double brace, E E', the lower end of which is hinged in bearings e, embedded in the river-bottom.

It will be observed that both ends of the 60 shutters C C' are free, and that their lower ends, in raising them into a vertical or approximately vertical position, will abut against a shallow step or sill, B, in the river-bed. A suitable distance in front of this sill I place 65 my abutment, which is denoted by the letter F, and is held firmly in the river-bed by its downward-projecting dovetailed transverse flanges f f', which may, however, sometimes be dispensed with where the river-bed is of a nature to admit it. This abutment, as will be seen more clearly by reference to Figs. 2 and 3 of the drawings, consists of a series of inclined planes, a b c, forming a series of steps or shoulders, (denoted by a' b' c') the part or 70 section a sloping off laterally or sidewise past the next sections, b and c, and divided from the latter by a ridge or flange, i, leading into the groove or channel d', while the inclined planes b c, in regular succession, open up into the 75 parallel groove or channel d.

Reference being now had to Fig. 1 of the drawings, the operation of my invention will readily be understood. The shutters to be raised into position to form the dam are stepped 85 against the sill B by means of the breech-chains g h, which are operated by means of a windlass, H, placed on top of the derrick G. It is obvious that instead of this derrick a traveling crane (operating one or more shutters 90 at a time) may be used; or a floating derrick may be employed, if desired. Other chains are suitably arranged and operated by the windlass for the purpose of bringing the top end of the shutters into proper position; but 95 these chains are relieved from all strain by means of the braces E D E' D', and the inclination of the shutters (by which the depth of water is, of course, regulated) is adjusted by means of the braces D D' and stepped 100 abutment F. If it is desired to lower the shutter into the position shown at C', it is first

raised until its brace D' slips, with its lower end, out over the inclined plane b into the channels or grooves a'' d', within which it will gradually assume a horizontal position, being guided into the converging channel or groove d, when it is again in a position to be raised through the inclined planes c b, with their stops or abutments, which regulate the pitch or inclination of the shutter.

10 It will thus be seen that no chains or other operating devices are necessary at the braces D D', which are operated automatically by the shutters and the stepped and channeled abutment F, in the manner described.

15 Having thus described my invention, I claim and desire to secure by Letters Patent of the United States—

1. The abutment F, provided with a series of inclined planes, a b c, having steps or shoul-

ders a' b' c', and grooves or ways a'' d' d, substantially as and for the purpose herein shown and specified.

2. The combination, with the adjustable shutters of a movable clough or dam and their braces, of the automatically-operating brace-abutment F, provided with a series of inclined planes, a b c, having steps or shoulders a' b' c', and grooves or ways a'' d' d, constructed and operating substantially in the manner and for the purpose herein shown and set forth.

25 In testimony whereof I have hereto affixed my signature in the presence of two subscribing witnesses.

30 ALFRED PASQUEAU.
